US0D1098090S

(12) **United States Design Patent** (10) Patent No.: **US D1,098,090 S**
(45) Date of Patent: ** Oct. 14, 2025

(54) **COVER FOR ELECTRONIC DEVICE**

(71) Applicant: **Samsung Electronics Co., Ltd.**, Suwon-si (KR)

(72) Inventors: **Bosoon Kang**, Suwon-si (KR); **Kangmoon Kim**, Suwon-si (KR); **Byoungjin Kim**, Suwon-si (KR); **Taeoh Kim**, Suwon-si (KR); **Junyong Song**, Suwon-si (KR); **Taekkyung Lee**, Suwon-si (KR); **Woohyeok Jeong**, Suwon-si (KR); **Junghyun Choi**, Suwon-si (KR)

(73) Assignee: **Samsung Electronics Co., Ltd.**, Suwon-si (KR)

(**) Term: **15 Years**

(21) Appl. No.: **29/962,066**

(22) Filed: **Sep. 10, 2024**

(30) **Foreign Application Priority Data**

Mar. 29, 2024 (KR) 30-2024-0012455

(51) **LOC (15) Cl.** **03-01**

CLAIM

The ornamental design for a cover for electronic device, as shown and described.

DESCRIPTION

FIG. 1 is a front perspective view of a cover for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an exploded front perspective view thereof showing an example stylus pen detached from the cover for electronic device.

The evenly-dashed broken lines in the figures depict portions of the cover for electronic device that form no part of the claimed design.

1 Claim, 9 Drawing Sheets
